(57) CLAIM

The ornamental design for a front cover for a handset, as shown and described.

DESCRIPTION

FIG. 1 is a bottom plan view of a front cover for a handset showing my new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a right side view thereof in an open position;

FIG. 10 is a front view thereof in an open position;

FIG. 11 is a left side view thereof in an open position;

FIG. 12 is a perspective front view thereof in an open position; and,

FIG. 13 is a perspective rear view thereof in an open position.

UNITED STATES PATENT AND TRADEMARK OFFICE
CERTIFICATE OF CORRECTION

PATENT NO. : Des. 482,686 S
DATED : November 25, 2003
INVENTOR(S) : Jarmo Lehtonen

Page 1 of 1

It is certified that error appears in the above-identified patent and that said Letters Patent is hereby corrected as shown below:

Title page.

Item [57], DESCRIPTION, insert the following sentence:

-- The broken line showing of the internal surfaces in FIGS. 6, 8, and 13 is for illustrative proposes only and forms no part of the claimed design. --

Signed and Sealed this

Sixteenth Day of November, 2004

JON W. DUDAS
Director of the United States Patent and Trademark Office
